UNITED STATES PATENT OFFICE.

FRED WRIGHT, OF WINNIPEG, MANITOBA, CANADA.

BUCKLE.

1,315,618.

Specification of Letters Patent.

Patented Sept. 9, 1919.

Application filed November 5, 1918. Serial No. 261,268.

To all whom it may concern:

Be it known that I, FRED WRIGHT, of the city of Winnipeg, in the Province of Manitoba, Canada, have invented certain new and useful Improvements in Buckles, of which the following is the specification.

The invention relates to improvements in buckles and the principal object of the invention is to provide a strap buckle which can be readily clasped or opened and which is not unsightly and which can be manipulated with one hand and which will positively hold the free end of the strap against undoing.

With the above general objects in view the invention consists essentially in the arrangement and construction of parts hereinafter more particularly described and later pointed out in the appended claim, reference being had to the accompanying drawing in which:

Figure 1 represents a perspective view of the buckle as in use.

Fig. 2 represents an enlarged detailed plan view of the closed buckle with the strap inserted therein.

Fig. 3 represents an enlarged detailed plan view of the open buckle with the strap inserted therein.

Fig. 4 represents an enlarged detailed plan view of the open buckle with the strap released.

Fig. 5 represents a cross sectional view through the buckle, the section being taken in the plane denoted by the line X—X' Fig. 2.

Fig. 6 represents an enlarged detailed longitudinal sectional view centrally through the buckle and strap, the section being taken in the plane denoted by the line Y—Y' Fig. 2.

Fig. 7 represents an enlarged detailed side view of a portion of the flange of the bottom plate.

Fig. 8 represents a vertical sectional view through the flange, the section being taken in the plane denoted by the line Z—Z' Fig. 7.

In the drawing like characters of reference indicate corresponding parts in the several figures.

This buckle is particularly adapted for use on the wrist strap of a watch where at present, with the ordinary form of buckle, considerable difficulty is experienced in fastening the strap on the wrist. Accordingly

I have shown my buckle as applied to a wrist strap as the advantages of it are very apparent in this location.

1 and 2 represent the customary strap ends of a wrist band, both of which are connected, as shown at 3, to the sides of the watch 4. To the end 2 of the band I connect my buckle 5 and here it is to be understood that the end 1 of the strap is fitted with the usual adjusting openings 6 for fastening purposes. The buckle is now described in detail.

7 represents an under receiving plate fitted at one end with a slotted extension 8 to which I fasten permanently the end 2 of the strap as best shown in Figs. 4 and 6. One edge of the plate is formed with an upstanding flange 9 which passes the full length of the plate and is provided more or less centrally of its length with an upstanding extension 10 fitted with a catch pocket or slot 11.

To the opposite side of the plate I secure pivotally, as indicated at 12, a top closure plate 13 which has the side remote from the hinge notched at 14 to receive the extension 10, the arrangement being such that when the cover plate is closed down on the flange it lies parallel with the bottom plate and reserves an opening equal to the depth of the flange between the top and bottom plates.

15 represents a fastening pin or stud extending upwardly from the bottom plate and positioned centrally of the width thereof, the arrangement being such that the pin can be readily entered into one or the other of the openings 6 when the top plate is open and the end 1 of the strap is drawn in over the bottom plate. The top plate is fitted with a countersunk opening 16 designed to receive the upper end of the stud upon the top plate being closed down.

17 represents a sliding latch or catch countersunk in a cross slot 18 formed in the underside of the top plate. The latch is held to the top plate by a pin 19 extending through a slot 20 provided in the plate and provided with a head or finger piece 21 which rides the outer face of the top plate. This catch has the end 22 tapered or beveled off so that when the top plate is swung down the catch engaging with the extension 10 will move back and will take a position immediately opposite the catch opening 11. A spring 23 is mounted in the underside of the top plate and engages the catch

- and is designed to press the catch continuously in the direction indicated by the applied arrow in Fig. 3 so that when the top plate is closed down as above intimated the 5 catch will primarily clear the extension and will then be forced in the direction of the arrow and under the action of the spring into the catch opening, thereby automatically locking the top plate to the flange.
- 10 With this buckle applied on a wrist band it is only necessary to take the thumb or finger and force the finger piece 21 in a direction which will allow the top plate to be opened up. The end 1 of the strap is then 15 caught and pulled over to allow of the pin 15 being entered into one or other of the openings 6. When this is accomplished there is no tendency for the strap to undo as the pin will hold it against slipping.
- 20 The fastening of the buckle is completed by simply closing down the top plate which automatically latches and positively locks the end 1 of the strap against withdrawing 25 from the stud or pin 15. The easy manner in which this article can be used renders it very convenient and serviceable and further

it has a pleasing effect as a buckle as it is not unsightly and it practically covers from view the connected ends of the strap.

What I claim as my invention is:—

30

A strap buckle comprising a bottom plate fitted at one end with attaching means and at one side with an upstanding flange having an extension thereon, a top plate pivotally secured to the other side of the bottom plate 35 and designed to close against the flange while reserving a strap receiving space between the plates, said top plate having one edge thereof notched to receive said extension, a spring-operated sliding catch carried 40 by the top plate and releasably locking the top plate to the flange in the closed position of the top plate, a finger piece for manipulating the catch and a stud extending from the bottom plate into the space between the 45 plates and through the inserted strap.

Signed at Winnipeg, this 5th day of October, 1918.

FRED WRIGHT.

In the presence of—

G. S. ROXBURGH,

K. B. WAKEFIELD.
